The ornamental design for a rope shackle attachment thimble, as shown and described.

DESCRIPTION

FIG. 1 is a left front perspective view of a rope shackle attachment thimble showing our new design.

FIG. 2 is a left side elevational view thereof, the right side elevational view being a mirror image of the left side elevational view.

FIG. 3 is a front elevational view thereof, the rear elevational view being the same as the front elevational view.

FIG. 4 is a top plan view thereof, the bottom plan view being the same as the top plan view; and,

FIG. 5 is a cross-sectional view thereof taken along line 5-5 of FIG. 4 illustrating better the shape of the central core of the rope shackle attachment thimble.

Internal structure shown with cross hatching in FIG. 4 is illustrative only and forms no part of the claimed design.
